UNITED STATES PATENT OFFICE.

CHARLES P. FAY, OF CHICOPEE, MASSACHUSETTS, ASSIGNOR TO THE
J. STEVENS ARMS AND TOOL COMPANY, OF SAME PLACE.

PROTRACTOR.

SPECIFICATION forming part of Letters Patent No. 665,316, dated January 1, 1901.

Application filed January 30, 1899. Serial No. 703,799. (No model.)

To all whom it may concern:

Be it known that I, CHARLES P. FAY, a citizen of the United States of America, and a resident of Chicopee, in the county of Hampden 5 and State of Massachusetts, have invented certain new and useful Improvements in Protractors, of which the following is a full, clear, and exact description.

This invention relates to improvements in 10 protractors of the class having combined with the graduated semicircular plate the centrally-pivoted radius-bar or protractor-arm, which is adapted to be swung at any angle from the base edge of the protractor-plate, 15 which description of protractor is extensively used by mechanics in setting bevel-squares or universal squares at any required angle, by draftsmen in setting T-squares with the blades thereof at any angle to the head, and 20 by architects, surveyors, and others.

The invention more particularly relates to 25 interlocking devices whereby the radius-bar or protractor-arm, after having been set at any angle required may be locked in its set 30 position and held safely against accidental displacement, but susceptible of being readily disengaged and afterward locked for a new setting of the bar, the object being to provide a protractor of the kind referred to which is 35 extremely simple and cheap of construction, very convenient in operation, and accurate in its measuring or angle-indicating capability.

The invention in its broader aspect is de- 40 fined as comprehending a new and improved protractor, consisting of a protractor-plate and a protractor-arm or radius-bar pivoted thereon, the plate having a series of teeth or serrations corresponding to the degree-gradua- 45 tions thereon and the arm having a member to register with the protractor-graduations and provided with a device adapted for convenient detachable engagements with the teeth of the plate; and the invention also con- 50 sists in the specific constructions and combi- 55 nations of parts, all substantially as shown, described, and set forth in the claims.

Reference is to be had to the accompany- 60 ing drawings, in which the present improved 50 adjustable protractor is fully and clearly illus- 65 trated, and in which—

Figure 1 is a plan view thereof. Fig. 2 is a sectional view on line 2 2, Fig. 1. Fig. 3 is an edge view of the protractor, showing the protractor-arm as swung into its position, 55 whereby it is disengaged from the protractor-plate to permit the adjustment of said arm at any angle from the base of said plate. Fig. 4 is a plan view of portions of the protractor-plate and of the protractor-arm, especially 60 illustrative of the provisions whereby the one is detachably interlocked with the other. Fig. 5 is a sectional view similar to Fig. 2, but showing a slight modification.

Similar characters of reference indicate cor- 65 responding parts in all of the views.

In the drawings, A represents the protractor-plate, of substantially semicircular form, having the straight base edge a, as usual, and having its face around adjacent its arc-formed 70 edge provided with the degree-indicating marks or graduations b, and the said arc-formed edge of the protractor is provided with a series of notches or teeth b, correspond- 75 ing to and one for each of the graduations.

B represents the radius-bar or protractor-arm lying under and next to the protractor-plate, being pivotally connected thereto by the headed screw f and clamp-nut g, the extremity of said arm projecting beyond the 80 toothed edge of the protractor-plate, said extremity having formed thereon or perma- 85 nently affixed thereto a member or shoe h, which is provided at its inner edge with sev- 90 eral teeth i, which are adapted to engage in the teeth edgewise provided on the protractor-plate. The height of the shoe, as shown, is approximately the same as the thickness of the plate, and the same is provided with the upstanding stud j, having at its upper end the 95 overhanging head m. The height of the stud is slightly greater than the thickness of the plate, and the head m is inwardly beveled, as indicated at n, and is centrally provided with an indicating mark or line o, extending 100 centrally and longitudinally relative to the protractor-arm.

In order to adjust the protractor-arm, which is of thin spring metal, the stud is pressed downwardly to bring the bevel-head to over- 100 lap and lie closely on the upper face of the protractor-plate, thereby causing the shoe h

to be moved clear below the lower face of the protractor, the teeth of the shoe being disengaged from the teeth of the protractor-plate, all as clearly indicated in Fig. 3. The protractor-arm is now swung until the indicating-line o on the head of the stud comes to the graduation indicating the number of degrees at which the protractor is to be set, whereupon the downward pressure is released, permitting the teeth i of the shoe h to match into and interlock with the teeth of the plate, firmly assuring the retention of the bar in its given set position, so that there will be no liability when the instrument is placed against an adjustable square or other tool or work of the arm becoming displaced from its set position.

While the description hereinabove given is specific in detailed statement of the precise forms or constructions and arrangements of the parts of the protractor as shown in the drawings, I may, under the foregoing statement of invention and the terms of certain of my claims, carry out my invention by the employment of substantially the same idea of means, but somewhat different in matters of detail—as, for instance, I may provide the protractor-arm B with the member or device for engaging the serrations or teeth of the protractor-plate, which member is movable on or relative to the arm proper for the engagement and disengagement with the teeth of the plate, and in Fig. 5 the radius-bar or protractor-arm B is constructed in the two sections o and o^2 , the one of which is engaged with the other for an endwise sliding movement, as permitted by the pin-and-slot engagement, (indicated at t .) Therefore under this construction a distention of the radius-bar, instead of a bending thereof across its normal plane of occupancy, enables the disengagement of the teeth i of the part h at the outer extremity of the bar from the teeth or serrations at the edge of the protractor-plate.

Having thus described my invention, what I claim, and desire to secure by Letters Patent, is—

1. A protractor-plate having a series of degree-graduations, and provided with a series of corresponding teeth, combined with a protractor-arm pivotally connected to swing around on the plate, carrying an indicating

part to register with the said graduations, and having a part movable relatively to the teeth of the plate, to engage and disengage 55 the same.

2. A protractor-plate having graduations, and edgewise provided with corresponding teeth, combined with the pivotally-connected protractor-arm constructed with a portion or 60 member projected beyond the edge of the plate, and provided with an upstanding part which at its edge toward the plate is toothed, the said arm which carries the upstanding part being composed of spring metal and capable of being swung transversely of the plane 65 of the plate for disengagement and reengagement with the latter, substantially as described.

3. A protractor-plate having graduations 70 and edgewise provided with teeth corresponding thereto combined with a protractor-arm of spring metal pivotally connected to the plate and having at its extremity which is projected beyond the edge of the plate, the 75 upstanding shoe h which at its edge toward the plate is toothed, and said extremities furthermore having the upstanding stud with the head which overhangs the edge of the protractor-plate, and which has an indicator 80 to register with the graduations of the plate, substantially as described.

4. The combination with the protractor-plate having the degree-graduations and corresponding edgewise serrations or teeth, of 85 the protractor-arm B pivotally connected to the base portion of the plate and having its free extremity extended beyond the curved edge of the plate and provided with the shoe h having at its edge toward the plate the 90 teeth i and having the upstanding stud j of a height slightly greater than the thickness of the plate and provided with the head m which overhangs the edge of the plate, and which has the beveled part n provided with the indicating-mark o , all substantially as described 95 and shown.

Signed by me at Springfield, Massachusetts, this 4th day of November, 1898.

CHARLES P. FAY.
